DESIGN FOR A COMBINED INSIGNIA EASEL PICTURE FRAME AND ADVERTISING MOUNT

Samuel E. Parker, Dunkirk, Ind.

Application June 17, 1944, Serial No. 114,046

Term of patent 14 years

(Cl. D29—20)

To all whom it may concern:

Be it known that I, Samuel E. Parker, a citizen of the United States, residing at Dunkirk, in the county of Jay and State of Indiana, have invented a new, original, and ornamental Design for a Combined Insignia Easel Picture Frame and Advertising Mount, of which the following is a specification, reference being had to the accompanying drawing, forming part thereof.

In the drawing:

Fig. 1 is a front elevational view of a combined easel picture frame and advertising mount, showing my new design, and

Fig. 2 is a vertical cross section taken on line 2—2 of Fig. 1.

I claim:

The ornamental design for a combined insignia easel picture frame and advertising mount, as shown.

SAMUEL E. PARKER.
